UNITED STATES PATENT OFFICE.

DORA JONES, OF NEW YORK, N. Y.

CONDIMENT-HOLDER.

No. 818,649.

Specification of Letters Patent.

Patented Feb. 27, 1906.

Application filed August 30, 1905. Serial No. 276,354.

To all whom it may concern.

Be it known that I, DORA JONES, a citizen of the United States, residing in the city of New York, in the county and State of New York, have invented certain new and useful Improvements in Condiment-Holders, of which the following is a specification.

My invention relates to holders for salt, powdered sugar, and other similar articles, particularly those of a deliquescent character, and especially to the common type of table-holder which is provided with a perforated top or cap through which its contents are discharged.

One object of my improvements is to provide a simple, sightly, and efficient means of keeping the moisture of the atmosphere from the contents of the holder, thereby preventing the caking of the contents and the stoppage of the perforations, which render the holders at times almost useless, and also for keeping out dust, insects, &c.

A further object is to provide an adjustable cover which may be attached to the common table-holders already in use.

I attain these objects by certain novel features of construction and combination of parts, as hereinafter described and as illustrated in the accompanying drawings, in which—

Figure 1 is a plan of a salt-holder embodying my improvements; Fig. 2, an enlarged section of the cap and cover of the holder; Fig. 3, a plan, and Fig. 4 a section, of a modified form of my improvements.

Similar reference characters indicate corresponding parts in the several figures.

The holder 1, as shown in Figs. 1 and 2, is the common table-holder, made in any suitable shape and of any suitable material. To the cap 2, provided with the usual perforations 3, is hinged, as at 4, a cover 5, the lower surface of which is or may be concave or flat in conformity with the shape of the top of the cap. The cover is automatically closed and normally held closely down upon the top of the cap by a coiled spring 6, which is mounted on the pivot of the hinge, or by any other suitable means. Attached to the lower surface of the cover, so as to be inter-

posed between it and the top of the cap when the cover is closed, is a yielding or elastic pad 7, which is preferably made of cotton or woolen felt or other similar absorbent material and is or may be detachably secured to the cover by means of a shouldered recess 8 therein or by gum or cement, so that it may be readily removed and renewed as often as may be found desirable.

In the form shown in Figs. 3 and 4 the cover, with the elastic pad attached thereto, is hinged, not directly to the cap, but to a band 9, by which it can be adjustably secured to the cap of any of the ordinary table-holders now in common use. For the purpose of adapting it to somewhat varying sizes of caps the band is preferably made of resilient material and split at one side, as at 10, although equivalent means for securing an adjustable connection between the band and the cap of the holder may be employed. In this case the central portion 5^a of the cover is preferably made of a hollow dome shape to accommodate the central upward projection, if any, on the top of the cap with which it is used. By making a few different sizes of covers and bands the attachment may be adapted for use with nearly all of the common table-holders.

What I claim as new, and desire to secure by Letters Patent, is—

1. In a holder of the character described, the combination of a perforated cap, a cover hinged thereto and adapted to cover the perforations therein and a pad of absorbent material interposed between it and the top of the cap when the cover is closed.

2. In a holder of the character described, the combination of a perforated cap, a cover hinged thereto, a pad of absorbent material detachably secured within a shouldered recess in the lower side of the cover, and a spring adapted to keep the cover normally closed over the perforations in the cap.

In witness whereof I have hereunto affixed my signature in the presence of two witnesses.

DORA JONES.
